TRUCK BED CANOPY

Alfred F. Easter, 13045 26th NE., Seattle, Wash.

Filed Oct. 29, 1964, Ser. No. 82,372

Term of patent 14 years

(Cl. D14—27)

FIG. 1

FIG. 3

FIG. 1 is a front perspective view of a truck bed canopy showing my new design, the vehicle is included for illustrative purposes only;

FIG. 2 is a side elevation view thereof; and

FIG. 3 is a back elevation view thereof.

The side not shown is the same as the side illustrated in FIGS. 1 and 2.

I claim:

The ornamental design for a truck bed canopy, as shown and described.
